UNITED STATES PATENT OFFICE.

EDWARD L. MEGILL, OF BROOKLYN, NEW YORK.

FEED-GAGE FOR PRINTING-PRESSES.

SPECIFICATION forming part of Letters Patent No. 289,014, dated November 27, 1883.

Application filed June 27, 1881. (Model.)

To all whom it may concern:

Be it known that I, EDWARD L. MEGILL, a citizen of the United States, residing at Brooklyn, in the county of Kings and State of New York, have invented a new and useful Feed-Gage for Printing-Presses, of which the following is a specification.

My invention relates to feed-gages which are fastened to the platen, and has for its object to furnish an effective, reliable, and simple registering apparatus.

My invention consists, first, in means of varying the position of the gage-head, or that part against which the sheets are directly fed under and along the gage-shanks, or that part sustaining the gage-head, for the purpose of allowing the sheets to go under the forward end of the gage-shanks any required distance; second, in the arrangement and construction of the feed-gage, whereby a firm hold and pressure of the gage-head at any part of the platen is obtained, and the usual objectionable methods of either running the shanks of the gages far out beyond the limits of the platen, or jointing the gages, or penetrating the platen-paper, or such methods as would prevent the use of the press-nippers, are avoided; third, in an eccentric or oblong plate operated at the gage-head, and so arranged that while the gage-shank is set at one angle over the platen-sheet the said plate may be set at another by turning to the right or left, thus varying the direction and distance of the said plate over margins of sheets fed to the gage-heads, independent of the position of the gage-shanks as secured to the holders; and, fourth, in an improved construction of the gage-holders.

In the accompanying drawings, Figure 1 is a perspective view of the platen of a printing-press with a set of my new feed-gages attached, holding a sheet in place. Dotted lines represent the gages turned down to the extreme lower edge of the platen. Fig. 2 is an edge view of one of the feed-gages removed, showing in dotted lines the different positions of the gage-head under the gage-shank, and also in dotted lines the lower part of the holder before it is fitted to the platen-band. Fig. 3 is an edge view of the holder differently arranged, and secured to a half-round platen-band. Fig. 4 is a top view of the gage withdrawn from the

holder, in which dotted lines show the spring-plate turned crosswise. Fig. 5 is a top view of the holder. Fig. 6 is a perspective view of the gage-head removed from the shank. Fig. 7 is a perspective view of the spring-plate removed.

Similar letters refer to similar parts throughout the several views.

The platen A, platen-bands B B, platen-paper C, with my feed-gages attached, constitute the platen equipped for printing and registering the sheets D.

Of my feed-gages, E is a bracket of pliable metal, which has a deep notch in the lower end to provide two (or more, if desired) narrow projections, F F, which are easily bent by hand, and fitted around the platen-band, of whatever style or shape it may be. The said bracket is provided on top with a jaw, G, extending forward parallel to the lower part, forming a mouth, into which the shank K of the gage is inserted for fastening. This jaw prevents the shank K from displacement when tightening the same by the screw H, and serves to hold the washer I up. The screw H passes through a hole in the said jaw, and through the end of the gage-shank K and into the threads of the block J, the latter being firmly riveted below to the bracket G.

K, the gage-shank, is cut from sheet metal and notched at the rear end to admit the screw H when sliding it into the mouth of the holder. The forward end of said gage-shank is provided with screw-holes at various distances apart, into which the gage-head L is screwed, according to the position required. Said gage-head is of solid metal, which may be depressed or hollowed out at the bottom to form an edge for impressing the platen-paper, and a slot may be made on the head or screw for the use of a tool to tighten it on the shank; or a plug may be substituted for the screw and plain holes for the screw-holes.

M is a plate perforated out of the center, to allow the screw (or plug) of the gage-head to pass through to the gage-shanks, and upon which it revolves to present in any direction a long or short projection over the margin of the sheet. The plate may be made with several tongues of various lengths branching in different directions, or may be reduced to a simple eccentric. The drawings represent an

oblong plate with a single hole out of the center; but more holes may be put therein in any part of its length.

The feed-gages are operated as follows: The 5 holders or brackets are first fitted to the platen-band by bending the lower projections around the back of it, which may be done by the press-man. The holders are then set the required distance apart and the platen-band forced down 10 on the edge of the platen. The gages are then set into the mouth of the holders and turned—one to the right and the other to the left—until brought to the correct position for the sheet. If required, at the lower part of the platen, for 15 a narrow sheet, the gage-heads may be set into the holes nearest the holders. The eccentric plate or spring-tongue M is then adjusted over the margin at any length or angle by revolving the same. If a stiff projection is required, the shank may be made to extend by 20 setting the gage-head back. When all is arranged, the screw of the holder is tightened.

These feed-gages will be made of all sizes, and may be modified and cheapened for simple 25 work.

What I claim is—

1. In a feed-gage for printing-presses, the combination of a gage-shank with a gage-head having suitable fastenings for adjusting, varying, and securing the latter under and along 30 the former, whereby the sheets are allowed to go under the forward end of the gage-shanks any required depth, substantially as herein set forth.

2. An eccentric or elongated plate pivoted 35 at or by the gage-head, and arranged to be turned so as to project at various angles and distances over the margins of the sheets, substantially as set forth.

3. The combination, in a registering apparatus for printing-presses, of the gage-head L, pivoted eccentric, elongated plate M, and gage-shank K, substantially as herein described. 40

4. In a registering apparatus, the combination of the spring jaw or clamp with the pivoted gage-shank, substantially as and for the 45 purpose herein described.

EDWARD L. MEGILL.
